H. L. MILLER

HYDRAULIC CONVEYER VALVE

Filed Sept. 3, 1925

UNITED STATES PATENT OFFICE.

HENRY L. MILLER, OF MOBILE, ALABAMA.

HYDRAULIC CONVEYER VALVE.

Application filed September 3, 1925. Serial No. 54,286.

This invention relates to valve devices, and particularly to that type known as hydraulic conveyer valves.

The principal object of the invention is 5 the production of a simply and efficient means for supplying water to the mouth of the dredge for the purpose of dislocating any foreign substance or clogged matter from the mouth of the dredge.

10 With the foregoing and other objects in view, my invention comprises certain combination, constructions and arrangement of parts as will be illustrated in the accompanying drawings, described in the following 15 ing specification, and more particularly pointed out in the appended claims.

In the drawings:

Figure 1 is a view partly in elevation and partly in section of a valve device constructed in accordance with the present invention, while—

Figure 2 is a top plane view of the same.

Figure 3 is a sectional view taken on line 20 3—3, Figure 1, and looking in the direction 25 of the arrows.

Figure 4 is a sectional view taken on line 4—4, Figure 1, and looking in the direction or the arrows.

Referring to the drawings by numerals, 30 1 designates the suction tube and 2 is the water supply pipe of a dredge. On the inlet end of pipe 2 is a strainer 3. A valve casing 4 is placed intermediate the ends of pipe 2, and is attached to suction tube 1 by 35 horizontal plate 5. The inner end of pipe 2 empties into suction tube 1, at 6 near the inlet end of said pipe 1. Valve 7 is mounted on stem 8, in casing 4, and said stem 8 is pivotally connected to arm 9. Arm 9 is 40 fixedly mounted on the outer end of shaft 10. Shaft 10 extends into housing 11, which housing is formed upon tube 1. A plate 12 closes opening 13, through which opening fin 14 is placed, to locate it within tube 1.

45 The upper end of fin 14 is fastened to shaft 10. A stub 15 is formed upon the top of fin 14 and shackle bolt 16 is pivotally fastened at its lower end, to stud 15. The upper 50 end of bolt 16 is threaded, and this threaded end extends into hood 17; hood 17 is fastened to plate 12 above the fin 14. A cover 18 is on the hood 17. A nut 19 is on the bolt 16, within hood 17, and this nut is provided with a rounded or convex lower face, to 55 permit said nut to have a "rolling" action

against the inner face of hood 17 when the fin 14 moves. A lock nut 20 is threaded on bolt 16 against nut 19. By screwing the nuts 19 and 20 down tight, the valve 7 will be locked upon its seat. The bolt 16, hood 17 and nuts therein also prevents the back pressure affecting fin 14 should pumping stop or cease.

When the apparatus is in operation, it is submerged in a river or other stream where it is desired to dredge the channel or deepen the harbor. A high pressure suction is applied to the tube 1, so as to draw mud, sand, clay and like soft material therethrough, these elements being drawn into the tube 70 or pipe 1 adjacent the points 6 (in the drawings) and through this tube with great velocity under normal conditions. When the force of velocity of water passing through said tube 1 is decreased because of 75 clogging adjacent the intake end thereof, the fin 14 will fall, so as to remove the valve 7 from the valve seat in casing 4. Since the supply tube or pipe 2 is also submerged, it will be filled with water when the valve 7 80 is removed from its seat. The suction with in the main tube 1 will cause the water to be expelled from the supply pipe 2 and strainer 3 into the suction pipe or tube 1 with considerable force. Since the supply 85 pipe 2 will cause the water to be discharged into the suction tube 1 at right angles to the passage of the liquid through said tube, the water from the supply pipe 2 will strike with sufficient force in suction tube 1 to wash away sand, clay and mud which might be 90 clogging the intake of tube 1. The action of the inflow of water into the tube 1 is similar to the manner sides of hills are sometimes washed by streams from hose lines 95 for washing out metal.

While I have described the preferred embodiment of my invention, and have illustrated the same in the accompanying drawings, certain minor changes or alterations 100 may appear to one skilled in the art to which this invention relates, during the extensive manufacture of the same and I, therefore, reserve the right to make such alterations or changes as shall fairly fall within the 105 scope of the appended claims.

What I claim is:

1. In a device of the class described, the combination of a suction tube, a supply pipe communicating with said suction tube, 110

valve means for closing said supply pipe, a fin in said suction tube, a hood on said suction tube opposite to said fin, a bolt connected at one end to said fin and having its 5 other end positioned in said hood, nuts in said hood and threaded on said bolt, and means operatively connecting said fin and valve means together.

2. In a device of the class described, the 10 combination of a suction tube provided with an opening, a plate closing said opening, a hood on said plate, a fin in said suction tube under said plate and hood, a supply pipe provided with valve means communi-

cating at one end with said suction tube, an 15 upstanding stud on said fin, a bolt pivotally connected at its lower end to said stud and having its upper end extending through the plate and into said hood, a convex or rounded face nut threaded on said bolt with- 20 in said hood, a lock nut threaded on the bolt against said first-mentioned nut, and means movably connecting said fin and valve means together.

In testimony whereof I hereunto affix my 25 signature.

HENRY L. MILLER.
